FLUE STOP

Filed March 14, 1929

FIG. 1.

FIG. 2.

FIG. 3.

Inventor

E. H. Raines.

By *A. F. Randolph Jr.*

Attorney

UNITED STATES PATENT OFFICE

EDWIN H. RAINES, OF URBANNA, VIRGINIA, ASSIGNOR OF ONE-HALF TO ELWIN S. MUIRE, OF URBANNA, VIRGINIA

FLUE STOP

Application filed March 14, 1929. Serial No. 347,051.

The invention relates to an improved means for closing flue openings and has for its principal object the provision of a means for holding a cover plate on flue openings that will effectually hold the plate in position against outward pressure from the chimney and thus providing an absolutely fire-proof cover for the flue opening.

A further object of the invention is the provision of a flue stop comprising a cover plate for the flue opening, and having mounted thereon a fixed pin and a spring actuated pin to engage the wall of the flue opening on opposite sides thereof, the spring actuating the pin being of sufficient tension to hold the plate in covering position against any air pressure in the chimney.

A further object of the invention is the provision of a cover plate for flue openings having an inwardly extended bracket secured thereto and having a pin adjustably secured on said bracket and another pin slidably mounted on the bracket, and spring actuated, said pins extending in opposite directions from the bracket and adapted to engage the wall of the flue on opposite sides of the opening to securely hold the cover plate in position.

The invention will be described in detail hereinafter and will be found illustrated in the accompanying drawings in which

Figure 1 is a transverse sectional view of a flue opening showing the cover plate in position thereon and in section,

Figure 2 is a sectional view on a plane indicated by the line 2—2 of Figure 1, and

Figure 3 an end view in elevation of the securing means detached from the cover plate.

In the drawings similar reference characters are used to designate corresponding parts throughout the several views.

The cover plate 1 may be circular or any other shape desired and is preferably formed of sheet metal and adapted to close the opening to a flue or chimney designated A. Secured to the inner side of the plate 1 is a U-shaped bracket 2, said bracket being adapted to be secured in any suitable manner, including flanges 3 extending outwardly of the arms 4 of the bracket secured by means of

bolts or other fastening members 5. 6 designates a pin having one end threaded as shown at 7 and adjustably secured in the arms 4 by means of nuts 8 arranged on opposite sides of one of said arms 4, the other and outer end of said pin 6 being tapered to a point as shown at 9 to engage the wall of the flue A as shown in Figures 1 and 2. 10 indicates another pin that is slidably mounted in the arms 4 and having a head 11 at one end thereof that provides a stop to limit the movement of the pin by engaging the bracket 2, while its other end is tapered to a point as shown at 12 and provided with a threaded portion 13 to receive a nut 14 and a washer 15 forming an abutment to receive the thrust of an expandable coil spring 16 enclosing said pin 10 and terminally engaging the adjacent arm 4 of the bracket 2. The nut 14 also provides means by which the tension of the spring 16 may be regulated as desired for the most effectual operation of the device, while the pin 6 may be adjusted by means of the nuts 8 to provide for mounting the securing means in flue openings of different dimensions.

In operation it will be apparent that the device is mounted in the flue by inserting the pin 10 in advance of the pin 6 and by pressing the end of the pin 10 against the wall of the flue opening to compress the spring 16, so the pin 6 may be then inserted into the opening and pressure on the spring 16 being released the pointed ends 9 and 12 of the pins 6 and 10, respectively, will engage the wall of the flue opening on opposite sides thereof and effectually hold the cover plate 1 in position.

What is claimed is:—

1. A flue stop, comprising a plate adapted to cover a flue opening, a pin secured thereto and adapted to engage the wall of the opening, a pin slidably mounted on the plate and adapted to engage the wall of the opening, and spring means projecting the last mentioned pin and holding the pins in engagement with said wall.

2. A flue stop, comprising a plate adapted to cover a flue opening, a bracket secured to said plate, a pin secured to the bracket, another pin slidably mounted on said bracket,

and a spring to project said pin, said pins being adapted to engage the wall of the flue and hold the plate in position.

3. A flue stop, comprising a plate adapted to cover a flue opening, a bracket secured to said plate, a pin adjustably secured to the bracket, another pin slidably mounted on the bracket, an expansible coil spring enclosing the pin and engaging the bracket, and an adjustable abutment on the pin, said spring normally projecting the pin, the pins being adapted to engage the wall of the flue and hold the plate in position.

4. A flue stop, comprising a plate adapted to cover a flue opening, a U-shaped bracket secured to said plate, a pin secured to said bracket, means to adjust the pin on the bracket, another pin slidably mounted on the bracket, a head on one end of the pin limiting the movement of the pin in one direction, an abutment adjustably secured to the pin, and an expansible coil spring enclosing the pin and terminally engaging the bracket and abutment to project the pin, said pins being adapted to engage a wall on opposite sides of the flue opening to hold the plate in position.

In testimony whereof I affix my signature.

EDWIN H. RAINES.
